DESIGN FOR A DISPENSING CLOSURE FOR SALT CELLARS AND THE LIKE

Arthur Hammerstein, Palatine, Ill.

Application June 22, 1945, Serial No. 120,255

Term of patent 14 years

(Cl. D44—22)

To all whom it may concern:

Be it known that I, Arthur Hammerstein, a citizen of the United States and resident of Palatine, in the county of Cook and State of Illinois, have invented a new, original, and ornamental Design for Dispensing Closure for Salt Cellars and the like, of which the following is a specification, reference being had to the accompanying drawing forming part thereof, and in

which Fig. 1 is a side elevation of the closure showing the new design; Fig. 2 is a similar view looking at right angles to Fig. 1, and Fig. 3 is a plan view of the closure.

I claim:

The ornamental design for a dispensing closure for salt cellars and the like, as shown.

ARTHUR HAMMERSTEIN.
